HATCH CONSTRUCTION

Charles David Bonsall, Pittsburgh, Pa., assignor
to P. H. Murphy Company, New Kensington,
Pa., a corporation of Pennsylvania

Application April 13, 1936, Serial No. 74,218

16 Claims. (Cl. 108—5.4)

My invention relates to the hatch construction of a metal car roof. It has for its principal objects to devise a strong and durable hatch construction of simple, economical and weather-proof construction and to attain other advantages hereinafter appearing. The invention consists in the hatch construction and in the combinations and arrangements of parts herein-after described and claimed.

10 In the accompanying drawings, which form part of this specification and wherein like symbols refer to like parts wherever they occur,

Fig. 1 is a plan view of the end portion of a car roof provided with a hatch construction embodying my invention.

Fig. 2 is a vertical partial transverse section through the roof on the line 2—2 of Fig. 1.

Fig. 3 is a vertical partial longitudinal section through the roof on the line 3—3 of Fig. 1.

20 Fig. 4 is a perspective view of one of the plates for reinforcing and stiffening the hollow rim portion of the metal hatch frame.

Fig. 5 is an enlarged fragmentary section similar to Fig. 2 through one side of the hatchway.

25 Fig. 6 is an enlarged fragmentary section similar to Fig. 3 through one side of the hatchway.

Figs. 7, 8 and 9 are views similar to Fig. 6 illustrating three modified forms of hatch construction.

30 Fig. 10 is a fragmentary plan view similar to Fig. 1 illustrating another modified form of hatch construction.

Fig. 11 is a fragmentary plan view of the frame-work that defines the hatchway opening 35 of the construction shown in Fig. 10.

Fig. 12 is a vertical partial transverse section on the line 12—12 in Fig. 10.

Fig. 13 is a vertical partial longitudinal section on the line 13—13 in Fig. 10.

40 Fig. 14 is an enlarged fragmentary section similar to Fig. 12 through one side of the hatchway; and

Fig. 15 is an enlarged fragmentary section similar to Fig. 13 through one side of the hatchway.

In Figs. 1 to 6 of the accompanying drawings, my invention is shown in connection with a metal refrigerator car roof comprising end and intermediate roof sheets 1 and 2, respectively, 50 that extend from side plate 3 to side plate 3 of the car with their eaves ends resting on and riveted or otherwise rigidly secured to the outstanding top flanges of eaves angles 4, whose depending flanges are riveted or otherwise rigidly secured to the upstanding inner side flanges of said side plates. The roof sheets are provided along their adjacent margins with upstanding flanges 5 that are straddled by a seam cap 6 that is riveted or otherwise secured to said 55 flanges and to the top flanges of the eaves angles

6 At the end of the car, the end roof sheet 1 is supported on and riveted or otherwise rigidly secured to the outstanding top flange of an end angle 7, whose depending inner side flange is riveted or otherwise rigidly secured to the upstanding inner side flange of an end plate 8.

The roof is provided with one or more hatchways that lead downwardly into the interior of the car through the end sheet and a framework located therebelow. Said framework comprises 10 spaced parallel frame or carline members 9 that extend from side plate to side plate with their ends rigidly secured thereto and themselves supporting spaced cross frame members 10. The carline members and cross members preferably 15 comprise oblique metal angles arranged with their tops flush and with their sides converging downwardly.

Each hatchway is provided with a metal frame comprising a hopper portion 12 that extends 20 downwardly through the opening defined by the frame members 9 and 10 with its downwardly converging sides resting flatwise against the inclined sides thereof. Said hopper portion also

extends upwardly above the general level of the 25 roof sheets where it is provided with an exterior, downwardly opening hollow rim portion 13 formed by a flange that extends outwardly from the upper end thereof and thence downwardly around sides thereof with its lower end spaced 30 above the general level of the end roof or hatch sheet 1. The hollow rim portion 13 of the metal hatch frame is reinforced and stiffened along its four sides by means of upright plates 14 that

rest upon the tops of the angle iron frame members 9 and 10 and extend upwardly into said rim 35 and have a snug fit therein. The plates 14 are

welded, as at 15, along their edges to the portions of the hatch frame in contact therewith and are also tack-welded, as at 16, at their lower edges 40 to the tops of the frame members 9 and 10. The lower portions of the plates 14 are widened to bring the outer edges 17 thereof in flush alignment with the outer surface of the depending outer wall of the hollow rim portion of the metal 45 hatch frame.

The end roof or hatch sheet 1 is provided above the opening defined by the frame members 9 and 10 with an opening of substantially the same size and shape as the rim portion of the metal 50 hatch frame and an upstanding flange 18 along the margin of said opening. This flange bears against the exposed outer edges 17 of the lower portions of the plates 14 with its upper edge disposed substantially in the plane of the lower edge 55 of said rim portion and with its inner face disposed substantially in flush alignment with the outer face of the depending outer wall thereof.

The upstanding hatch sheet flange 18 is rigidly 60 secured to the depending outer wall of the hollow

rim portion 13 of the metal hatch frame by means of a weld 19 of added metal that extends along the top edge of said flange and along the outer face of said depending wall.

5. In the modified construction shown in Fig. 7, the upper end of the hopper portion of the metal hatch frame is provided with a mere outstanding flange 20; and the upstanding flange 18a along the margin of the opening in the hatch sheet has its upper edge disposed substantially flush with the underside of said outstanding flange. The roof sheet flange and hatch sheet flange are secured together by a weld 19a of added metal that extends along the adjacent edges of said flanges.
15. In the modified construction shown in Fig. 8, the top flange 21 of the metal hatch frame is made narrower than the top flange 20 of the hatch frame shown in Fig. 7; and the upstanding hatch sheet flange is provided at its top with an inwardly extending portion 18b that abuts edgewise against the outer edge of the hatch frame flange. The hatch frame flange and roof sheet flange are rigidly secured together by a weld 19b of added metal that extends along the tops of said flanges above the joint therebetween.

In the modified construction shown in Fig. 9, the metal hatch frame is made without a top flange and the hatch sheet flange has an inwardly extending portion 18c at its upper end that is disposed flush with the upper of said hatch frame and abuts edgewise against the side thereof. The metal hatch frame and roof sheet flange are secured together by a weld 19c of added metal that covers the joint therebetween.

35. The modified form of hatch construction shown in Figs. 10 to 15, inclusive, is similar to that shown in Figs. 1 to 6, inclusive, except that the carline members and the cross members of the hatch supporting framework or carline assembly have their outer marginal portions of their top flanges bent up opposite the hatch opening in said framework to form upstanding flanges 22 that are disposed in line with the depending outer wall of the hollow hatch frame rim, with their upper edges spaced slightly below the lower edge of said wall. A weld 23 fills the spaces between the opposing edges of the upstanding frame member flanges 22 and the edge of the depending outer wall of the hollow hatch frame rim and thus serves to rigidly secure said metal hatch frame to the supporting framework therefor. The upstanding flange 18d along the margin of the opening in the hatch sheet is secured along its upper edge to the lower end of the outer wall of the hatch frame rim by means of a weld 19d that forms a rigid weatherproof connection between the hatch frame and hatch sheet.

The hatch construction hereinbefore described has numerous advantages. The cross plates in the hollow rim portion of the metal hatch frame serve as ties and struts for preventing distortion thereof; they also serve to locate the lower edge of the outer wall of the hollow hatch frame rim level with the upper edge of the hatch sheet flange and to bring the outer surface of said wall and the inner surface of said flange in flush alignment so that said wall and said flange may be welded together in proper relation; and they also afford means for welding the hatch frame to the supporting framework therefor. The metal hatch frame can be applied to the car with the framework as a separate unit, or it may be welded to the framework after the latter is applied to the car. The hatch sheet can be removed without removing the hatch frame; and,

likewise, the hatch frame can be removed without removing the hatch sheet. In the hatch construction shown in Figs. 10 to 15, inclusive, the upwardly flanged margins of the top flanges of the frame members of the framework provide means for welding the hatch frame thereto; and they also serve to properly position the hatch sheet flange relative to the depending outer wall of the hatch frame rim.

What I claim is:

1. A hatch construction for a car roof comprising a roof sheet provided with a hatch opening having an upstanding flange along the margin thereof, and a self-contained metal hatch frame extending downwardly through said opening and upwardly above the general level of said roof sheet, members rigid with said roof and disposed in abutting relation to the inner side face of said upstanding flange, and means for rigidly securing the upper margin of said upstanding flange to the margin of the upwardly extending portion of said metal hatch frame.

2. A hatch construction for a car roof comprising a roof sheet provided with a hatch opening having an upstanding flange along the margin thereof, a self-contained metal hatch frame extending downwardly through said opening and upwardly above the general level of said hatch sheet, members rigid with said roof and spaced apart around said hatch frame in abutting relation to the inner side of said upstanding flange, means for rigidly securing the upper margin of said upstanding flange to the margin of the upwardly extending portion of said hatch frame, and means for rigidly securing said members to said hatch frame.

3. A hatch construction for a car roof comprising a metal roof sheet provided with a hatch opening having an upstanding flange along the margin thereof, a self-contained metal hatch frame extending downwardly through said opening and upwardly above the general level of said roof sheet, metal members rigid with said roof and spaced apart around said metal hatch frame in abutting relation to the inner side of said upstanding flange, a weld securing the upper margin of said upstanding flange to the margin of the upwardly extending portion of said metal hatch frame, and welds securing said metal members to said metal hatch frame.

4. A hatch construction for a car roof comprising a roof sheet provided with a hatch opening having an upstanding flange along the margin thereof, spaced frame members located beneath said hatch opening, a self-contained metal hatch frame extending downwardly through said opening and the space between said frame members and upwardly above the general level of said roof sheet, and means rigid with said frame members and said hatch frame disposed in abutting relation to the inner side of said upstanding flange.

5. A hatch construction for car roofs comprising a metal roof sheet provided with a hatch opening having an upstanding flange along the margin thereof, spaced metal frame members located beneath said hatch opening, a self-contained metal hatch frame extending downwardly through said opening and the space between said frame members and upwardly above the general level of said roof sheet, with its margin welded to the upper margin of said upstanding flange, and upright plates resting on and welded to said frame members and spaced apart around the upwardly extending portion of said metal hatch frame and welded thereto.

6. A hatch construction for car roofs comprising a roof sheet provided with a hatch opening having an upstanding flange along the margin thereof, a self-contained metal frame extending downwardly through said opening and upwardly above said upstanding flange, the upwardly extending portion of said hatch frame being provided with an exterior downwardly opening hollow rim portion whose lower edge terminates substantially in the plane of the upper edge of said upstanding flange, and a weld for securing said lower edge of said rim portion to said upper edge of said upstanding flange. 5
10. A hatch construction for car roofs comprising a roof sheet provided with a hatch opening having an upstanding flange along the margin thereof, a self-contained metal frame extending downwardly through said opening and upwardly above said upstanding flange, the upwardly extending portion of said hatch frame being provided with an exterior downwardly opening hollow rim portion whose lower edge terminates substantially in the plane of the upper edge of said upstanding flange, and a weld for securing said lower edge of said rim portion to said upper edge of said upstanding flange. 10
15. A hatch construction for car roofs comprising a roof sheet provided with a hatch opening having an upstanding flange along the margin thereof, a self-contained metal frame extending downwardly through said opening and upwardly above said upstanding flange, the upwardly extending portion of said hatch frame being provided with an exterior downwardly opening hollow rim portion whose lower edge terminates substantially in the plane of the upper edge of said upstanding flange, and a weld for securing said lower edge of said rim portion to said upper edge of said upstanding flange. 15
20. A hatch construction for car roofs comprising a roof sheet provided with a hatch opening having an upstanding flange along the margin thereof, a self-contained metal frame extending downwardly through said opening and upwardly above said upstanding flange, the upwardly extending portion of said hatch frame being provided with an exterior downwardly opening hollow rim portion whose lower edge terminates substantially in the plane of the upper edge of said upstanding flange, and a weld for securing said lower edge of said rim portion to said upper edge of said upstanding flange, the outer side face of said rim portion and the inner side face of said upstanding flange being disposed in substantially flush alignment. 20
25. A hatch construction for car roofs comprising a roof sheet provided with a hatch opening having an upstanding flange along the margin thereof, a self-contained metal hatch frame extending downwardly through said opening and upwardly above said upstanding flange, said hatch frame being provided above said upstanding flange with an exterior downwardly opening hollow rim portion, the depending outer wall of said hollow rim portion being rigidly secured at its lower end to the upper end of said upstanding flange, and web plates located in said hollow rim portion crosswise thereof. 25
30. A hatch construction for car roofs comprising a roof sheet provided with a hatch opening having an upstanding flange along the margin thereof, a self-contained metal hatch frame extending downwardly through said opening and upwardly above said upstanding flange, said hatch frame being provided above said upstanding flange with an exterior downwardly opening hollow rim portion, the depending outer wall of said hollow rim portion being rigidly secured at its lower end to the upper end of said upstanding flange, and web plates located in said hollow rim portion crosswise thereof. 30
35. A hatch construction for car roofs comprising a roof sheet provided with a hatch opening having an upstanding flange along the margin thereof, a self-contained metal hatch frame extending downwardly through said opening and upwardly above said upstanding flange, said hatch frame being provided above said upstanding flange with an exterior downwardly opening hollow rim portion, the depending outer wall of said hollow rim portion being rigidly secured at its lower end to the upper end of said upstanding flange, and web plates located in said hollow rim portion crosswise thereof. 35
40. A hatch construction for car roofs comprising a roof sheet provided with a hatch opening having an upstanding flange along the margin thereof, a self-contained metal hatch frame extending downwardly through said opening and upwardly above said upstanding flange, said hatch frame being provided above said upstanding flange with an exterior downwardly opening hollow rim portion, the depending outer wall of said hollow rim portion being rigidly secured at its lower end to the upper end of said upstanding flange, and web plates located in said hollow rim portion crosswise thereof. 40
45. A hatch construction for car roofs comprising a roof sheet provided with a hatch opening having an upstanding flange along the margin thereof, a self-contained metal hatch frame extending downwardly through said opening and upwardly above said upstanding flange, said hatch frame being provided above said upstanding flange with an exterior downwardly opening hollow rim portion, the depending outer wall of said hollow rim portion being rigidly secured at its lower end to the upper end of said upstanding flange, and web plates located in said hollow rim portion crosswise thereof with their lower ends extending below said hollow rim portion and abutting against the inner side of said upstanding flange. 45
50. A hatch construction for car roofs comprising a roof sheet provided with a hatch opening having an upstanding flange along the margin thereof, a self-contained metal hatch frame extending downwardly through said opening and upwardly above said upstanding flange, said hatch frame being provided above said upstanding flange with an exterior downwardly opening hollow rim portion, the depending outer wall of said hollow rim portion being rigidly secured at its lower end to the upper end of said upstanding flange, and web plates located in said hollow rim portion crosswise thereof with their lower ends extending below said hollow rim portion and abutting against the inner side of said upstanding flange. 50
55. A hatch construction for car roofs comprising a roof sheet provided with a hatch opening having an upstanding flange along the margin thereof, a self-contained metal hatch frame extending downwardly through said opening and upwardly above said upstanding flange, said hatch frame being provided above said upstanding flange with an exterior downwardly opening hollow rim portion, the depending outer wall of said hollow rim portion being rigidly secured at its lower end to the upper end of said upstanding flange, and web plates located in said hollow rim portion crosswise thereof with their lower ends extending below said hollow rim portion and abutting against the inner side of said upstanding flange. 55
60. A hatch construction for car roofs comprising a roof sheet provided with a hatch opening having an upstanding flange along the margin thereof, a self-contained metal hatch frame extending downwardly through said opening and upwardly above said upstanding flange, said hatch frame being provided above said upstanding flange with an exterior downwardly opening hollow rim portion, the depending outer wall of said hollow rim portion being rigidly secured at its lower end to the upper edge of said upstanding flange, upright web plates located in said hollow rim portion crosswise thereof with their lower ends extending below said hollow rim portion and abutting against the inner side of said upstanding flange, and spaced frame members located beneath said openings and supporting said plates. 60
65. A metal hatch frame for a car roof comprising a hopper portion provided at its upper end with an exterior downwardly opening hollow rim portion, and web plates located in said rim portion crosswise thereof with their lower end portions extending below said hollow rim portion, the outer side edges of said lower portions of said plates being disposed in substantially flush alignment with the outer side face of said hollow rim portion, as and for the purposes described. 65
70. A metal hatch frame having a body portion adapted to extend into the hatch opening of a car roof sheet, and outstanding plates secured edgewise to said body portion and adapted to be disposed in abutting relation to the edge of said hatch opening, as and for the purpose described. 70
